Primary Examiner — Cynthia M. Chin(74) *Attorney, Agent, or Firm* — Craft Chu PLLC;
Andrew W. Chu(57) **CLAIM**

The ornamental design for a water movement device, as shown and described.

DESCRIPTION

FIG. 1 is an end perspective view of the water movement device showing my design;

FIG. 2 is a front elevation view thereof;

FIG. 3 is an end elevation view thereof;

FIG. 4 is a side elevation view thereof;

FIG. 5 is a back elevation view thereof;

FIG. 6 is an opposite end elevation view thereof;

FIG. 7 is an opposite side elevation view thereof; and,

FIG. 8 is a front elevation view thereof, showing an attachment in broken lines.

The broken lines in FIGS. 1 & 8 are for the purpose of illustrating attachments to the article that form no part of the claimed design.

1 Claim, 4 Drawing Sheets*FIG. 1*

FIG. 2

FIG. 3

FIG. 4
